UNITED STATES PATENT OFFICE.

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY.

METHOD OF MAKING SHOES.

1,419,203.

Specification of Letters Patent. Patented June 13, 1922.

Original application filed June 15, 1916, Serial No. 103,747. Divided and this application filed November 12, 1920. Serial No. 423,631.

To all whom it may concern:

Be it known that I, ARTHUR BATES, a subject of the King of England, residing at Leicester, Leicestershire, England, have invented certain Improvements in Methods of Making Shoes, of which the following description, in connection with the accompanying drawings, is a specification, like reference characters on the drawings indicating like parts in the several figures.

This invention relates to methods of making shoes, and particularly to that part of shoe manufacture in which the upper is shaped in conformity to the contour of a last or other shoe form, the present application being a division of my earlier application Serial No. 103,747, filed on June 15, 1916. The invention has in view the provision of a method adapted to secure improved results in the making of welt or other shoes wherein the margin of the upper is worked inwardly over the bottom of the last, for example into lasted relation to a sole or insole, hereinafter generally termed for convenience the "sole," but it will be understood that in some of its aspects the invention is not limited to the manufacture of shoes of this particular type.

In the lasting of welt shoes particular difficulties are involved in shaping the upper tightly over the toe of the last and over the feather of the sole without the presence in parts of the upper that are visible in the completed shoe of wrinkles which tend to form ahead of the wipers as the margin of the upper is gathered within a contracted area inwardly from the edge of the sole. With the object, among others, of eliminating such difficulties in the lasting of welt and other shoes, the present invention provides a method whereby in the shaping of upper materials inwardly over the bottom of a form or last the pressures are so distributed and the margin of the upper so controlled as to afford no opportunity for wrinkles to form as the upper is worked inwardly from the edge of the last bottom. For the purposes in view, the practice of the method in the manner herein illustrated comprises working the margin of the upper inwardly over a sole with substantially uniform pressure all round the toe by the aid

of a self-conforming wiper member, for example a flexible loop wiper, while clamping or gripping the margin of the upper in such manner as to hold it continuously smooth and free from wrinkles. Further to secure the desired results, the manner herein illustrated of practicing the method involves also such control of the margin as to give up stock at any point or points where excessive tension is produced by the indrawing pull of the wiper, thus assisting in equalizing the strains while providing the requisite upper stock for the overwiping operation.

In a further aspect, the invention has in view the stretching and pulling of the upper over the top of the forepart of the last in addition to working it inwardly about the last, for example, over the bottom of the last as above set forth, the practice herein illustrated involving the giving up of stock from the clamped margin both in stretching it heightwise of the last and in working it inwardly over the last bottom. Since substantially less pressure on the margin of the upper is required to control it in the desired manner during the operation of working it inwardly about the last than in pulling and stretching the upper heightwise of the last, the invention further provides for relaxing the clamping pressure after the upper pulling operation, thus facilitating, for example, the overwiping of the upper to its finally shaped or lasted position.

The novel method of this invention, in the above mentioned and other aspects, will now be more particularly set forth by reference to the accompanying drawings which illustrate the various steps and show one form of apparatus by the aid of which the method may be practiced, such apparatus being more fully shown and described in my prior application of which this is a division.

In the drawings:

Fig. 1 is a view illustrating the treatment of a shoe, in accordance with one manner of practising the method, by the aid of the machine shown and described in said prior application, the head portion of the machine being shown in side elevation;

Fig. 2 shows the shoe and parts of the structure of Fig. 1 as they appear at an

earlier stage in the practice of the method; Fig. 3 is a view in front elevation illustrating more fully certain parts of the machine that are used in carrying out the 5 method;

Fig. 4 illustrates the manner of applying a toe binder to the shoe;

Fig. 5 is a detail illustrating the manner of fastening the binder to the shoe; and

10 Fig. 6 shows the toe of a shoe as it appears after having been lasted in accordance with the method of this invention.

Since the construction of the machine herein shown is fully described in my prior 15 application, it will be described herein only in as far as is necessary for an understanding of the method of this invention. The machine has a sole rest 1 and opposite side grippers 2, the sole rest being depressed to 20 some extent in the upper pulling operation by means of a cam 4 on the main cam shaft 5. The side grippers are connected to up-draw levers 6 which are operated to pull the upper at the ball of the shoe through springs 25 7 and a cam slide 8, the grippers being under the control of springs 7^x which move them subsequently inward to overdraw the upper under the control of a slide 124. At the end of the upper pulling operation the 30 machine comes automatically to rest for inspection of the upper. When the machine is again started side clamps 9 are swung inwardly into engagement with the shoe to hold it during the overlaying and fastening 35 operations, the fastening tacks being driven by tackers 10.

For clamping the margin of the upper outspread round the toe of the last the machine has a clamping plate 16 provided with 40 a recess the edge of which approximates the contour of the shoe round the toe, and a co-operating similarly shaped clamp member 25. The plate 16 is mounted to slide in a plane substantially parallel to the plane of 45 the shoe bottom, and is connected by a link 18, a bell-crank 19, a link 20, a lever 21, and a rod 22 to a treadle (not shown) that is yieldingly upheld in such manner as to maintain the plate 16 normally in its rear- 50 most position while permitting it to be moved forwardly by the treadle when a shoe is to be presented to the machine. In an upwardly extending portion of the clamp member 25 is swiveled a member 23 which is 55 perforated to receive the lower end of a rod 24 depending from one arm of a bell-crank 28 which is pivoted at 29 to an angle lever 30. A nut on the lower end of the rod 24 is arranged to engage the member 23 to raise 60 the clamp member when the rod is moved upwardly. The angle lever 30 is suspended from the front arm 32 of a bell-crank 35 which has a rear arm connected by a link 36 to a lever 40 similar to the side updraw 65 levers 6 and unyieldingly connected at its

rear end by a link 38 to a cam slide similar to the slide 8. The clamp member 25 is permitted to tip somewhat lengthwise of the shoe to adjust itself to differences in thickness of the stock, and is moved downwardly 70 by the mechanism above described through a spring 45 which encircles the rod 24 between a shoulder on the upper end of the rod and a washer engaging the member 23.

Before the shoe is presented to the machine the plate 16 is moved forwardly by its treadle, and the shoe is then positioned against the sole rest with the margin of the upper materials extending within the side gripper jaws and outspread round the toe 80 over the plate 16 which is then released to permit it to move rearwardly against the end face of the shoe. Upon the starting of the machine the clamp member 25 is yieldingly depressed to clamp the margin of the upper 85 outspread on the plate 16 on a continuous line round the toe, and the upper is then pulled by the updraw movement of the side grippers and by the downward movement of the last relatively to the clamping members 90 16 and 25. As the last is thus depressed, the upper is drawn tightly over the top of the forepart, and at any point or points where excessive tension is produced by reason of differences in the contour of the last the 95 clamping members permit the margin of the upper to slip, thus giving up stock in response to the pull and substantially equalizing the strains on different portions of the upper. With the upper thus pulled and held 100 under tension, as shown in Fig. 2, the machine comes automatically to a stop to permit inspection and any necessary adjustment of the upper.

For drawing or wiping the upper inwardly 105 round the end of the last and over the feather of the sole, the machine is provided with a flexible loop wiper 60 which is a permanent part of the machine and is adapted to be placed round the toe of the shoe immediately 110 below the plate 16 while the machine is at rest after pulling the upper. The loop extends backwardly along each side of the machine over guide rolls 62 and has its ends fastened to brackets 64 on a slide 222 which is reciprocated by a cam 225 on the cam shaft in engagement with a roll 65 on the slide, the slide 222 being the same slide by 115 which the side clamp arms 9 are operated. It will thus be understood that when the 120 machine is started the second time the flexible loop wiper 60 is pulled rearwardly and draws and wipes the margin of the upper inwardly over the feather of the sole all round the toe and against the rib or shoulder 125 of the sole, as illustrated in Fig. 1. During this overwiping operation the clamp members 16 and 25 permit the margin of the upper to slip at points of excessive tension, thus rendering the pressure of the wiper 130

substantially uniform along all portions of the margin of the upper. Meantime the margin is held continuously in an outspread and unwrinkled condition round the toe, and as the flexible wiper engages the upper close to the clamping means and close to the edge of the shoe bottom no opportunity is afforded for wrinkles to form in the overwiping operation. As the wiper is pulled inwardly, the clamping plate 16 is also permitted to move inwardly in response to the pull of the wiper, such inward movement being assisted further by the treadle spring connected as hereinbefore described to the means which operates said plate. By reason of such inward movement of the plate 16 the plate is maintained in close relation to the flexible wiper throughout the overwiping operation, which is of further assistance in preventing the formation of wrinkles. It will be understood that in this second stage of the cycle of the machine the slide 124 is slightly retracted, permitting the springs 7* to press the side grippers part way inward laterally of the shoe in directions for overdrawing the upper.

Since less clamping pressure on the margin of the upper is required to control the upper properly in the overwiping operation than is required in stretching the upper heightwise of the last, it is desirable to facilitate the overwiping action by relieving somewhat the clamping pressure. It will be noted by reference to Fig. 1 that the upper arm of the lever 28 is connected to a spring 55 which tends to pull it rearwardly, and that it carries a detent 56 the rear end of which abuts against the front end of a slide 818* with which machines of the illustrative type are provided for controlling the overdrawing movements of the grippers and the operation of the tackers. When the machine is started the second time, the slide 818* receives a slight rearward movement from its dotted line position to its full line position (Fig. 1), thus permitting the spring 55 to act on the lever 28 to swing the lower arm of the lever forwardly and upwardly. It will be noted that the lever 28 and the rod 24 constitute a toggle which in the upper pulling operation is held substantially straight by the slide 818* through the connections above described, this toggle being broken in consequence of the slight rearward movement of the slide 818*. In this way the clamping pressure on the margin of the upper is somewhat relaxed, permitting the margin of the upper to slip more readily as the flexible member 60 is drawn rearwardly to wipe the upper into lasted position.

The machine comes to a stop the second time with the parts in the position shown in Fig. 1, the upper being held in lasted position, by the flexible wiper. For fastening

the upper in this position the side tackers 10 are provided with means (Figs. 4 and 5) for holding a binder cord *a* across the lower ends of tack driver passages 75 so that the tacks will pass through the cord when they are driven. The cord is applied round the end of the shoe in the crease formed by the flexible wiper with the portions of the cord at the sides of the toe extending through the tackers, and the opposite ends of the cord are hooked into tensioning members 76, as indicated in Fig. 4. The cord having been thus arranged the machine is started for the third time, whereupon the side grippers complete their overdrawing movement and the side tackers also complete their inward movement and drive the tacks. The tackers, as shown in Fig. 4, have a component of rearward movement to assist in tightening the binder cord round the end of the shoe before it is fastened. After the tacks have been driven to fasten the binder cord, the parts of the machine immediately return to their starting positions and the shoe is released. It will be understood that before the shoe is removed the ends of the binder cord are to be disengaged from the members 76, or if desired the cord may be cut at the opposite sides.

It will be obvious from the foregoing description that, generally considered, the invention is not dependent upon the character of the member over which the upper is shaped, and the term "last" is accordingly to be understood as used herein in a generic sense and not by way of limitation.

Having explained the nature of the invention and set forth fully how it may be practiced, what I claim as new and desire to secure by Letters Patent of the United States is:

1. That improvement in methods of making shoes which consists in working the margin of an upper inwardly round the end of a last and over the feather of a sole on the bottom of the last into lasted relation to the rib or shoulder of the sole by the aid of a flexible wiper conformable at all points to the contour of the shoe, and while thus working the upper inwardly over the sole holding the margin of the upper clamped on a substantially continuous line round the toe to maintain the upper in an unwrinkled condition for the action of the flexible wiper.

2. That improvement in methods of making shoes which consists in working the margin of an upper inwardly round the toe end of a last over the margin of the bottom of the last by the aid of a flexible wiper conformable at all points to the contour of the shoe, and while thus working the upper inwardly over the bottom of the last holding the margin of the upper yieldingly against the pull of the wiper while giving up stock from the margin at points where an excess

of tension is produced by the indrawing pull of the wiper.

3. That improvement in methods of making shoes which consists in clamping the margin of an upper on a substantially continuous line round the toe of a last and holding the upper under tension and free from wrinkles, and then drawing the upper inwardly to the rib or shoulder of a sole on the bottom of the last by the aid of a flexible loop wiper while continuing to hold the upper under tension and giving up stock from the clamped margin at points where an excess of tension is produced by the indrawing pull of the wiper.

4. That improvement in methods of making shoes which consists in clamping the margin of an upper round the toe of a last and pulling the upper heightwise of the last, and drawing the upper inwardly to the rib or shoulder of a sole on the bottom of the last by the aid of a flexible loop wiper while holding the upper under tension and giving up stock from the clamped margin at points where excessive tension is produced by the indrawing pull of the wiper.

5. That improvement in methods of making shoes which consists in clamping the margin of an upper round the toe of a last and pulling the upper heightwise of the last while permitting the margin to slip at points where excessive tension is applied, and then drawing the upper inwardly into lasted position over a sole on the bottom of the last by the aid of a flexible wiper while continuing to hold the upper under tension and permitting the margin to slip in response to excessive tension.

6. That improvement in methods of making shoes which consists in clamping the margin of an upper round the toe of a last and pulling the upper heightwise of the last, and then relaxing the clamping pressure on the margin of the upper and drawing it inwardly round the toe of the last by the aid of a flexible loop member engaging it outside of the area of the clamped margin while permitting the margin to slip in response to the pull of said member.

50 7. That improvement in methods of making shoes which consists in clamping the margin of an upper round the toe of a last and pulling it heightwise of the last while giving up stock from the clamped margin at points of excessive tension to shape the upper under substantially uniform tension over the high and the low parts of the contour of the last, and then working the upper inwardly around the end of the last while holding the margin under a reduced pressure and giving up stock from the margin at points where the inward pull exceeds the resistance of such reduced pressure.

8. That improvement in methods of mak-

ing shoes which consists in clamping the 65 margin of an upper on a substantially continuous line round the toe of a last and pulling the upper heightwise of the last while maintaining the upper free from wrinkles around the toe, and then relaxing the clamping pressure on the margin of the upper while continuing to hold it free from wrinkles and drawing the upper inwardly to the rib or shoulder of a sole on the bottom 75 of the last by the aid of a flexible wiper 75 conformable at all points to the contour of the shoe.

9. That improvement in methods of making shoes which consists in clamping the margin of an upper outspread round the 80 toe of a last and pulling the upper heightwise of the last, and then drawing the upper inwardly over the bottom of the last by the aid of a flexible wiper while carrying the clamped margin inwardly and permitting it to slip at points where excessive tension 85 is produced by the pull of the wiper.

10. That improvement in methods of pulling over and lasting the foreparts of shoes which consists in clamping the margin of 90 an upper outspread round the toe of a last and independently gripping the margin also farther rearwardly at opposite sides of the forepart and pulling the upper heightwise of the last, and then reducing the clamping 95 pressure on the margin while continuing to hold it outspread and working the upper inwardly over the bottom of the last.

11. That improvement in methods of pulling over and lasting the foreparts of shoes 100 which consists in clamping the margin of an upper on a substantially continuous line round the end and along the sides of the toe of a last and independently gripping the margin also farther rearwardly at opposite sides of the forepart and pulling the upper heightwise of the last, and while continuing to hold the upper under tension round the toe pulling it inwardly over the bottom of the last by the aid of a flexible 110 wiper conforming at all points to the contour of the shoe.

12. That improvement in methods of making shoes which consists in clamping the margin of an upper round the toe end of 115 a last and holding the upper free from wrinkles round the toe, drawing the upper inwardly over the feather of a sole on the bottom of the last by the aid of a flexible loop wiper while continuing to hold the 120 upper free from wrinkles, and then applying a binder in the angle between the feather and the rib of the sole to hold the upper and removing the flexible wiper for use on another shoe.

In testimony whereof I have signed my name to this specification.

ARTHUR BATES.
